UNITED STATES PATENT OFFICE.

CHARLES COLAHAN, OF CLEVELAND, OHIO.

GRAIN-BINDER.

SPECIFICATION forming part of Letters Patent No. 361,346, dated April 19, 1887.

Application filed April 7, 1886. Serial No. 198,051. (No model.)

To all whom it may concern:

Be it known that I, CHARLES COLAHAN, of Cleveland, Ohio, have invented certain new and useful Improvements in Grain-Binders, 5 of which the following is a specification.

My invention relates to features in the general construction and operation of that class of binders in which the power-shaft is located beneath the binder-table, and the cord-holding 10 and knot-tying mechanism is supported on an overhanging arm above the binder-table.

My objects mainly are to produce a simple and inexpensive machine, and to provide 15 means for the adjustment of its parts and the successful operation of the same combined in one entire machine.

The means employed for perfecting the above object and the several features of my invention are particularly pointed out in the 20 specification and claims, reference being had to the accompanying drawings, which illustrate the same and convey a clear understanding of the application of the several parts and their combined operation.

25 Figure 1 is an end sectional view enlarged to show the double clutching-arms and the adjustable tripping-finger when the binder-arm is in its normal position beneath the binder-table prepared to receive the inflowing grain 30 for the formation of a bundle. This view also shows an intermittently-running wheel secured to the packer-shaft and carrying a clutching-pawl. Fig. 2 is a similar view showing the position of the double clutching-arms during 35 the binding of the bundle when the binder is in operation and the packers have been stopped. Fig. 3 is a perspective view of the adjustable tripping-finger and its adjustable supporting-plate, which is secured to the vertically-swinging arm in the usual manner. Fig. 4 is an end elevation showing the wrought T-iron frame and the gear-supporting cast-iron plate and the position and arrangement of the several parts in combined operation. Fig. 5 45 is a side elevation of the same, also showing a section of the wrought T-iron frame and the manner of securing the cast-iron gear-supporting plate and the bearings of the shafts thereon. Fig. 6 is a sectional view of the continuously- 50 running hollow shaft or sleeve and the inter-

mittently-running packer-shaft and the several parts that operate the binder and packers. Fig. 7 is a sectional view of the manner of securing the adjustable brace-rod which connects the wrought T-iron and the cast-iron frames together at the top over the binder-table. Fig. 8 is an end sectional view of the binder and gear-supporting frame. Fig. 9 is a detailed view of the tying-bill and its cam-wheel and the manner of supporting the same 60 and its main shaft on the wrought T-iron frame. Fig. 10 is a perspective view of the wrought T-iron frame.

A represents the wrought T-iron frame, 65 which is made of one piece.

B represents the cast-iron gear-supporting plate, which is secured to the wrought-iron frame in any desired manner.

B' is the bearing of the cam-wheel shaft in the gear-supporting plate B. 70

H, Fig. 9, are the bearings for the same shaft in the outer end of frame A. H also serves as the frame for the knotter-head.

J is the binder-arm shaft, which is supported at the outer end in the cast-iron plate. 75 The inner end is supported in bearing I, secured to the T-iron frame in any convenient manner.

T is the packer-shaft, which is also supported on the bearing I, and extends loosely 80 through the continuously-running sleeve T' and its bearings, and has on its outer end the sprocket-wheel H and its clutching-pawl.

Y and Y' are continuously-operating 85 sprocket-wheels, which receive motion from the harvester in the usual manner. It is intended to use but one of said sprocket-wheels at a time. They are firmly secured to the sleeve-shaft T', and the wheel Y has secured therein the clutch-pins b and b', which, when 90 in connection with the clutching-paws H' or H", will communicate motion alternately to the packer or the binder.

H is a sprocket-wheel secured to the packer-shaft, for communicating motion to the picker-fingers, which are of the usual form of construction, operating over the binder-table in connection with the packer-fingers, which operate beneath the binder-table. 95

On the sleeve-shaft T' is a pinion, Z, run- 100

ning loosely on its bearing, having secured thereto the clutching-pawl H'' , for connecting it to the continuously-running sprocket-wheel Y' , which is secured to the sleeve-shaft T'' , and which is provided with a clutching-pin, b' . The pinion Z gears with a cog-wheel, as shown, whereby the binder is operated in the usual way.

K and K' are the tripping-arms fitted loosely on the binder-arm shaft. The arm K is constructed and operated in the well-known manner of the Appleby type of machines, which alternately stop and start the binder in connection with its actuating-gear. K' , with its projecting point K'' , serves to catch and retain an additional clutching-pawl, which operates, in connection with the additional clutching-pin b , on the outside of the continuously-running wheel Y' .

o is a spring which forces the tripping-arm K' and its point K'' in contact with the clutching-pawl H' .

o' is an arm loosely pivoted on the binder-arm shaft, and is forced down by a lug on the arm K when said arm K is brought in contact with its clutching-pawl H'' , and thus forces the tripping-arm K' and its point K'' from contact with its clutching-pawl H' , and permits said pawl to clutch the packer-actuating clutch-pin b .

The construction just described is similar in some respects to that shown in my patent, No. 304,077, of August 26, 1884; but that patent does not show a continuous sleeve-shaft through which the packer-shaft extends and to which the wheel Y' is secured. In the patent mentioned the sleeve-shaft is in sections and has separate bearings, and the clutch-pins are not secured directly to the sprocket-wheel Y' .

o The tripping-fingers G and the tripping-rod l' are operated in the usual well-known manner.

L is the adjustable supporting-plate, to which the fingers G are adjustably secured.

P is the vertically-swinging arm.

g' is the removable adjusting-bolt, by which the plate L is held in place, and which secures the fingers G to said plate.

g is the guide-finger secured to the front of the tripping-finger G , said guide-finger passed loosely through the opening g' in the supporting-plate L . Said guide-finger g , which I have shown extending to the front from the tripping-finger G , parallel with the supporting-plate L , may be extended transversely therefrom, and may be adjusted in a guide-slot in the plate L .

g' is a rear extending arm, with a slot, g'' , to admit of its adjustment on the plate L .

a is a bearing in the plate B , to support the usual rock-shaft actuating the compressor, and is used in connection with the vertically-swinging arm P , which is pivoted to the heel of the binder-arm and actuated by the crank X' and

pitman X , Fig. 4, in the usual manner. I prefer, however, the construction shown in

Fig. 8, which attachment and operation of the compressor-arm, in connection with the binder-arm, forms part of the subject-matter of patent of Colahan and Rosback, No. 358,921, of March 8, 1887.

B^x and B^{xx} are sprocket-chains operating in connection with their respective wheels.

R is the adjusting brace-rod, attached at the lower end to the frame A by its bolt N^3 , and the upper end is secured in a projecting lug, N'' , cast on the gear-supporting plate B at B' . Said rod is provided with nuts N and N' to secure and adjust it at the upper end.

W is the cam-gear knotter operating wheel, 80 which is secured to its shaft S , and I have provided the downhanging knotter-supporting frame or head H^3 with support, which serves as a bearing for the shafts on each side of said knotter-operating wheel W . Said frame H^3 is secured to the frame A and the brace-rod R , which retains it firmly in its fixed position.

Z is the pinion provided with the clutching-pawl H'' , and actuates the binder in the usual well-known manner. Said pinion Z runs 90 loosely upon its bearing—the sleeve-shaft T' .

Having thus described my invention, what I claim, and desire to secure by Letters Patent, is—

1. The combination of the metallic frame 95 A and the plate B , detachably secured to the side of frame A , and extending above the top and below the bottom thereof, and provided with bearings for the several shafts of the binding mechanism, substantially as set forth.

2. The combination of the frame A , the shaft S , the cam gear-wheel W , mounted thereon, and the frame H^3 , supported by the frame A , and provided with a support for shaft S on each side of the cam and gear-wheel W , and with a 105 depending support for the knotting mechanism, substantially as set forth.

3. The combination of the frame A , the gear-supporting plate B , and the adjustable brace-rod R , connecting the frame with the 110 plate, substantially as shown and described.

4. The combination of the continuously-running sleeve-shaft T'' , having bearings at one end in the plate B , and its actuating sprocket-wheel Y' , provided with clutching-pins b b' 115 on opposite sides thereof for giving the alternate movements to the packer and binder, the pinion Z , loosely mounted on the sleeve-shaft T'' , and provided with the clutching-pawl H'' , the packer-shaft T , extending through the 120 sleeve-shaft, the bracket I , in which the packer-shaft has its bearings at one end, the bearings at its other end being provided by the sleeve-shaft, the packer-actuating sprocket-wheel H , located in close proximity to the sleeve-actuating wheel Y' , the clutching-paws $H' H''$, and the tripping-fingers K and K' , operating the latter upon the pawl H' and the former upon the pawl H'' , to permit the alternate clutching of the packer and binder.

5. The combination of the tripping-finger G , having the rear extending arm, g' , and its

slot g'' , and the front guide-arm, g , adjustable in an opening, g^4 , and the supporting-plate L , pivoted to the vertically-swinging arm P , to which it is secured by the adjusting-bolt g^3 , as 5 and for the purposes described.

6. The combination of the tripping-fingers G , the vertically-swinging arm P , the sup-

porting-plate, and the bolt g^3 , that secures both the plate and the tripping-finger to the arm, substantially as set forth.

CHARLES COLAHAN.
